HIS ATTORNEY

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

AIR-FEED CONTROL FOR STOPERS.

Application filed March 26, 1925. Serial No. 18,375.

To all whom it may concern:

Be it known that I, CHARLES C. HANSEN, a citizen of the United States, and resident of Easton, in the county of Northampton 5 and State of Pennsylvania, have invented a certain Air-Feed Control for Stopers, of which the following is a specification accompanied by drawings.

This invention relates to fluid actuated 10 rock drills of the hammer type, but more particularly to means for controlling the air feeding element of a stope drill.

Stope drills are usually equipped with a handle for controlling the rotation of the 15 drill steel. The handle thus provided may be used either as a means for rotating the machine and steel as a unit or for holding the machine against rotation in case the steel is rotated automatically. Ordinarily 20 this type of machine is provided with a pressure fluid feeding element for holding the steel against the work. Pressure fluid from the same source is admitted to the feed cylinder simultaneously with the admission 25 of pressure fluid to the hammer cylinder.

Whenever the steel binds or becomes stuck in the drill hole, it is preferable that the hammer continues to reciprocate while the machine is lowered somewhat to loosen the 30 steel. This is usually accomplished by releasing pressure fluid from the feed cylinder. Various means have been devised for accomplishing this result, usually requiring the other hand to be used, which is sometimes impossible due to the position and 35 location of the work. Also the construction has heretofore required a considerable number of movable parts and owing to the hard usage to which machines of this type are 40 ordinarily subjected, some difficulty has been experienced in maintaining fluid tight joints in the releasing mechanism.

It is accordingly an object of this invention to simplify the construction of air 45 feed controlling devices and insure ease and certainty of operation.

Another object is to produce an air feed controlling device in which the size of the exhaust passage may be varied for different 50 pressure volumes.

Other objects will be in part obvious and in part pointed out hereinafter.

The invention consists of the combination 55 of elements, features of construction and arrangement of parts having the general

mode of operation substantially as herein-after described and more particularly pointed out in the appended claims, and illustrated in the accompanying drawings, in which

Figure 1 is an elevation partly in section of a stope drill embodying the invention,

Figure 2 is an enlarged sectional view of a portion of a rotation handle showing the grip sleeve in normally upward position, and

Figure 3 is a view similar to Figure 2 showing the grip sleeve in a downwardly position to uncover the air feed exhaust 70 passage.

Referring to the drawings, the invention is embodied in a rock drill of the stoper type having a hammer cylinder A. A front head B is secured yieldingly to the front end of the cylinder A by side bolts C and springs D and supports a drill steel E. Disposed within the cylinder A is a reciprocating hammer piston (not shown) for delivering impact blows on the drill steel E. The drill steel may be rotated in any suitable manner, but in this instance is rotated by a gear motor (not shown) in a gear casing F.

A head block G forms a closure for the back end of the cylinder A and supports a laterally extending handle H. In this instance, the handle H serves as a means for preventing rotation of the machine with the drill steel E and has a projection J extending at right angles therefrom near its free end. A sleeve K arranged on the projection J serves as a grip for the operator and controls the release of pressure fluid from the feed cylinder. The handle H is provided with a passage L to permit the passage of pressure fluid therethrough.

The feeding element comprises a cylinder O secured to the head block G. A piston rod P carries a piston head Q at one end and at the other end supports a rock engaging pointer R.

Pressure fluid is supplied to the machine through a connection S and the admission of pressure fluid to the cylinders A and O is controlled by a suitable throttle valve (not shown) provided with a lever T. A passage U formed in the head block G establishes communication between the feed cylinder O and the passage L.

In order to regulate the exhaust of pressure fluid from the feed cylinder O for different pressure values, a plug V is inserted in an aperture W and has a passage 5 X which is controlled by a needle valve Y. Suitable means are provided for adjusting the valve Y and for this purpose a portion Z of the valve Y is screw threaded to cooperate with a corresponding screw threaded 10 portion b of the aperture W. The valve Y may be adjusted by inserting a screw driver in the screw slot c formed in the end of the threaded portion Z. A suitable nut d is screwed on the end of the threaded portion 15 Z of the valve to hold the valve in adjusted position.

In this instance the release of pressure fluid from the feeding cylinder is controlled by the sleeve K which is adapted to be 20 pulled downwardly on the projection J to uncover a passage e communicating at one end with the aperture W. The sleeve K is arranged slidably on the projection J and is held against rotation with respect thereto 25 by a rectangular aperture f in the sleeve which cooperates with a corresponding squared portion g of the projection J. Disposed within a recess h of the sleeve K is a spring k which bears at one end against 30 the wall o of the sleeve and the other end of the spring bears against a nut p screwed on the end of the projection J. The spring k automatically closes the sleeve when released by the operator and holds the sleeve 35 in a normally closed position.

Suitable means are provided for preventing leakage of pressure fluid from the ends of the sleeve K. To this end a packing q which may be of rubber, or other suitable 40 material, is arranged in a recess r of the sleeve K and is adapted to be pressed against a shoulder s of the projection J by the spring K. In order to seal the upper end of the sleeve K, a packing t is arranged 45 in a recess u at the juncture of the handle H at the projection J and provides a seat for the upper end of the sleeve.

By this arrangement of parts, the volume 50 of pressure fluid to be released from the feeding element is regulated by the needle valve Y which controls the passage X, and the position of the needle valve Y with respect to the passage X is determined by the line pressure. If, for instance, the machine 55 is attached to a low pressure air line, the space between the valve Y and the pas-

sage X may be increased; but on the other hand, if a higher line pressure is supplied, the space between the valve Y and the passage X is reduced accordingly.

By thus providing separate means for regulating the release of air from the feed cylinder for different pressure volumes, little or no thought is required on the part of the operator as to the correct position of the releasing mechanism for the immediate pressure, as the releasing position of the sleeve K is the same for all pressures.

I claim:

1. In a rock drill the combination of a fluid pressure feeding element, having an atmospheric vent, a rotation handle having a projection at an angle therefrom, a sleeve slidable longitudinally on said projection for releasing pressure fluid through the vent from the feeding element, a spring for holding the sleeve in normally closed position, and a normally stationary valve adapted to be adjusted for regulating the venting of pressure fluid from the feeding element.

2. In a rock drill the combination of a fluid pressure feeding element having an atmospheric vent, a rotation handle having a projection at an angle therefrom, a sleeve slidable longitudinally on said projection for releasing pressure fluid through the vent from the feeding element, and a normally stationary needle valve having a threaded portion and means whereby the valve may be adjusted for regulating the venting of pressure fluid from the feeding element.

3. In a rock drill the combination of a fluid pressure feeding element having an atmospheric vent with a rotation handle having a projection at an angle therefrom, a sleeve slidable longitudinally on said projection for releasing pressure fluid through the vent from the feeding element, a spring for holding the sleeve in normally closed position, said sleeve being held against rotation with respect to the projection, a spring for holding the sleeve in a normally inward position, a normally stationary needle valve adapted to be adjusted for regulating the venting of pressure fluid from the feeding element, and a packing in the sleeve cooperating with said projection to seal one end of the sleeve.

In testimony whereof I have signed this specification.

CHARLES C. HANSEN.
